RIBBON TYPE STRANDING MACHINE

Sherwood C. Hall, Kings Beach, Calif.

Application April 23, 1948, Serial No. 22,765

4 Claims. (Cl. 57—13)

1

This invention relates to rope or twine manufacturing machines, and more particularly to a machine for producing rope or twine of the type having a central core covered by twisted strands of folded strip material helically wound thereon.

A main object of the invention is to provide a novel and improved rope or twine-forming machine wherein twisted strands of longitudinally folded strip material are helically wound on a central core, the torsion applied to said strands being regulated in a definite manner so that all strands are uniformly twisted, whereby the resultant product is characterized by constancy in its strength and appearance along its length.

A further object of the invention is to provide an improved machine for forming rope or twine from transparent plastic material in ribbon form folded, twisted and helically wound on a suitable core, the torsion on the plastic ribbon material being definitely controlled and means being provided for coloring the core or applying luminous paint thereto, so that the core will show through the transparent wound covering and produce a decorative effect, whereby a rope of substantial strength, uniform characteristics and pleasing appearance is obtained.

Further objects and advantages of the invention will become apparent from the following description and claims, and from the accompanying drawings, wherein:

Figure 1 is a top plan view of a rope stranding machine constructed in accordance with the present invention.

Figure 2 is a fragmentary enlarged elevational view of the master bobbin wheel employed in the rope stranding machine of Figure 1.

Figure 3 is an enlarged longitudinal cross-sectional view taken through a ribbon folding die employed in the rope stranding machine of Figure 1.

Figure 4 is an enlarged transverse cross-sectional view taken on line 4—4 of Figure 3.

Figure 5 is an enlarged end view of the ribbon folding die of Figure 3 showing the strand forming slot through which the folded ribbon emerges from the die.

Figure 6 is an enlarged cross-sectional detail view taken on line 6—6 of Figure 1.

Referring to the drawings, 11 designates a hollow shaft which is journaled on suitable supports 12 and 13. Secured to support 12 is a base plate 14 on which is mounted a motor 15. Secured to the motor shaft is a gear 16 which meshes with a first gear 17 carried by shaft 11. Designated at 18 is a third-support, spaced from support 12 in

2

which shaft 11 is journaled. Shaft 11 carries a sprocket wheel 19 on the inner side of support 18 and a gear 20 on the outer side of said support.

Journaled on supports 13 and 18 parallel to shaft 11 is a shaft 21. One end of shaft 21 carries a gear 22. Rotatably mounted on support 18 is an idler gear 23 which meshes with gear 20 and with gear 22. The other end of shaft 21 carries a sprocket wheel 24. Rotatably mounted on shaft 11 adjacent support 13 is a female bevel gear 25 carrying a sprocket wheel 26. Sprocket wheel 26 is coupled to sprocket wheel 24 by a sprocket chain 27.

Secured to shaft 11 adjacent female bevel gear 25 is a master bobbin wheel 28. Journaled radially on master bobbin wheel 28 are a plurality of shafts 29, each carrying at its inner end a bevel gear 30 which meshes with the internal gear teeth of female bevel gear 25. Each radial shaft 29 carries at its outer end a bevel gear 31. Rotatably mounted in wheel 28 adjacent each bevel gear 31 is an inwardly inclined shaft 32 carrying a bevel gear 33 which meshes with the adjacent bevel gear 31. Secured to the end of shaft 11 is a wheel 34. Axially aligned with each shaft 32 and rotatably mounted in wheel 34 is a generally conical ribbon folding die 35 connected to the shaft 32 by an inwardly flanged channel bar 36.

Adjacent shaft 32 each channel bar 36 has bearing brackets 37 in which is rotatably supported a ribbon spool or bobbin 38. The channel bar 36 is formed to receive a ribbon 39 as said ribbon is unwound from the bobbin 38, as shown in Figure 6, and to guide the ribbon to the folding die 35.

Each folding die 35 has secured in its intermediate portion a pair of rearwardly tapered guide fingers 40, 40 spaced from the respective inside wall surfaces of the die and acting to fold the ribbon 39 to a generally U-shaped form as said ribbon passes through the space between the fingers and said inside wall surfaces. Rearwardly of said fingers the die has a depending tapered lug 41 and a pair of upstanding upwardly diverging fingers 42, 42 defining a V-shaped channel with respect to lug 41. The sides of the ribbon 39 are folded inwardly over the rear ends of fingers 40, 40 as it reaches this channel while passing through the die and when the ribbon 50 passes the channel it is folded to four thicknesses thereof. The die 35 has a rear wall 43 formed with a slot 44 aligned with the longitudinal plane of the aforesaid V-shaped channel, the folded ribbon passing through said slot.

Secured to the wheel 34 by means of brackets

45 in axial alignment with and rearwardly adjacent each folding die 35 is a hollow conical forming head 46 through which the folded ribbon passes. The forming head 46 engages the folded ribbon with sufficient friction to hold the ribbon firmly while it is being twisted, as will be subsequently described, by the axial rotation of folding die 35, without transmitting torsion rearwardly to that portion of the ribbon which has already passed through the forming head.

Designated at 47 is a strand die which is mounted on a suitable support 48 in axial alignment with shaft 11.

Journalized in supports 12 and 13 parallel to shaft 11 is a shaft 49 which also extends rotatably through support 48. At its forward end, shaft 49 carries a sprocket wheel 50 which is coupled by a suitable chain to sprocket wheel 19. At its rear end shaft 49 carries a gear 51. Designated at 52 is a housing in which is journalized a shaft 53 carrying bevel gears 54 and 55 on its intermediate portion and carrying respective gears 56 and 57 at its end portions. Gear 57 meshes with an idler gear 58 rotatably mounted on housing 52, said idler gear being in mesh with gear 51. These are ratio gears and they determine the length of lay desired in the strand. Journalized in housing 52 is another shaft 59 carrying a gear 60 which meshes with gear 56. Connected to the end of shaft 59 by a universal joint 61 is a shaft 62 journaled in a bearing bracket 63, shaft 62 carrying a bevel gear 64. Journalized in a supporting bracket 65 and provided with a conventional friction clutch 66 is a shaft 67 carrying a bevel gear 68 which meshes with bevel gear 64. Coupled to the end of shaft 67 is one end of a shaft 69, the other end of shaft 69 being rotatably supported in a bearing bracket 70. Shaft 69 carries a winding drum 71 upon which the finished rope is wound.

Journalized in housing 52 are shafts 72 and 73 carrying bevel gears 74 and 75 respectively meshing with the bevel gears 54 and 55. Carried on the ends of shafts 72 and 73 are respective grooved pulleys 76 and 77 in longitudinal alignment with strand die 47. An idler roller 78 is provided between the pulleys 76 and 77. The finished rope, shown at 79, emerging from strand die 47, passes over the drive pulley 76, under idler pulley 78, over drive pulley 77 and thence to the winding drum 71.

Rotatably mounted on brackets 80, 80 forwardly adjacent the forward end of shaft 11 is a drum 81 on which is wound suitable core material, such as manila, java, cotton, or the like, shown at 82. The core material extends through hollow shaft 11 and through the strand die 47 where the formed ribbon material is wound thereon. A paint dispensing head 83 may be mounted around the forward end of shaft 11 by means of a bracket 84 connected to support 18, the head 83 being centrally apertured to allow the core 82 to pass therethrough. Head 83 may receive paint from a suitable source by means of a supply conduit 85. The paint is deposited on the core as said core moves rearwardly through the shaft 11.

In operation, motor 15 rotates shaft 11 by means of the meshed gears 16 and 17. Shaft 21 is driven from shaft 11 through gears 20, 23 and 22. Female bevel gear 25 is driven from shaft 21 through sprocket wheel 24, chain 27 and sprocket wheel 26. Shafts 29 are rotated by the meshing engagement of bevel gears 30 with the internal gear teeth of female bevel gear 25. Shafts 75

32 are driven through gears 31 and 33. The folding dies 35 are therefore rotated with respect to wheels 28 and 34 while said wheels are simultaneously rotated around the axis of shaft 11, which contains the stationary core 82. Torsion is applied to the folded ribbon emerging from the folding dies 35, the torsion being effective only between the dies 35 and the forming heads 46. The twisted formed ribbon emerging from the heads 46 is wrapped around the core 82 in the strand die 47. Shaft 53 is driven through sprocket wheel 19, sprocket wheel 50, shaft 49, gear 51, gear 58, and gear 57. Shafts 72 and 73 are driven respectively through gears 54, 74 and 55, 75. Pulleys 76 and 77 therefore produce tension in the finished rope. Shaft 69 is driven by shaft 67 through clutch 66, gears 68 and 64, shafts 62 and 59 and gears 60 and 56. Additional tension in the finished rope is therefore produced by the rotation of winding drum 71.

It will thus be seen that the machine folds the ribbon strand material in the dies 35, twists the formed ribbon between the dies 35 and 46, and then winds the formed and twisted ribbon on the core 82 in the stationary strand die 47 while tension is being continuously applied to the emergent finished rope product.

By using transparent plastic ribbon material to form the twisted strands, such as cellophane or the like, a finished rope product is obtained which has great strength, is moisture repellent and resistant to soaking, is buoyant, and is attractive in appearance. The rope product is also uniform in its characteristics throughout its length.

While a specific embodiment of a rope manufacturing machine has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A rope forming machine comprising a hollow shaft, a first wheel carried by said shaft, a second wheel longitudinally spaced from said first wheel member also carried by said shaft, a plurality of bobbins rotatably mounted on said first wheel, folding dies rotatably mounted on said second wheel in axial alignment with the respective bobbins, means connecting the aligned bobbins and folding dies, forming dies carried by said second wheel in axial alignment with said folding dies, an annular stationary strand die axially aligned with said shaft, and means for simultaneously axially rotating said shaft and rotating the folding dies and bobbins around the axis of the respective aligned folding and forming dies.

2. A rope forming machine comprising support means, a hollow shaft journaled in said support means, a first wheel member carried by said shaft, a second wheel member rearwardly spaced from said first wheel member also carried by said shaft, a plurality of shaft elements rotatably mounted on said first wheel member, a bobbin carried by each shaft element, generally conical hollow folding dies rotatably mounted on said second wheel member in axial alignment with the respective shaft elements, means rigidly connecting the folding dies and the shaft elements aligned therewith, forming dies carried by said second wheel member rearwardly of and in axial alignment with said folding dies, a stationary

annular strand die spaced rearwardly of said shaft and axially aligned therewith, and means for simultaneously axially rotating said shaft and axially rotating the shaft elements with respect to said first wheel member.

3. A rope forming machine comprising support means, a hollow shaft journaled in said support means, a first wheel member carried by said shaft, a second wheel member carried by said shaft rearwardly spaced from said first wheel member, a bevel gear rotatably mounted on said shaft, a plurality of radial shaft elements journaled on said first wheel member, gear means coupling said shaft elements to said bevel gear, bobbin shafts journaled in said first wheel member, means coupling each bobbin shaft to a radial shaft element, a bobbin rotatably mounted on each bobbin shaft, generally conical hollow ribbon folding dies rotatably mounted on said second wheel member in axial alignment with the respective bobbin shafts, means rigidly connecting the folding dies to the bobbin shafts aligned therewith, forming dies carried by said second wheel member rearwardly of and in axial alignment with said folding dies, a stationary annular strand die spaced rearwardly of said shaft and axially aligned therewith, and means for simul-

taneously axially rotating said shaft on said support means and rotating said bevel gear on said shaft.

4. A rope forming machine comprising support means, a hollow shaft journaled in said support means, a winding drum rotatably mounted transverse to and spaced rearwardly from the rear end of said shaft, spaced first and second wheel members carried by said shaft, a plurality of bobbin shafts rotatably mounted in the forward wheel member, bobbins rotatably carried on said bobbin shafts, generally conical hollow ribbon folding dies rotatably mounted in the rear wheel member in axial alignment with the respective bobbin shafts, means rigidly connecting the folding dies to the bobbin shafts aligned therewith, forming dies carried by said rear wheel member rearwardly of and in axial alignment with said folding dies, a stationary annular strand die between the rear end of said shaft and said winding drum and axially aligned with said shaft, and means for simultaneously rotating said shaft on said support means, said bobbin shafts in said forward wheel member, and said winding drum.
